UNITED STATES PATENT OFFICE.

BARNIM L. BEHRENDT, OF BROOKLYN, NEW YORK.

CONTAINER FOR DISINFECTANTS.

1,149,890.

Specification of Letters Patent. Patented Aug. 10, 1915.

Application filed July 10, 1913. Serial No. 778,305.

To all whom it may concern:

Be it known that I, BARNIM L. BEHRENDT, a subject of the Emperor of Germany, and a resident of Brooklyn, county of Kings, and State of New York, have invented certain new and useful Improvements in Containers for Disinfectants, of which the following is a specification.

This invention relates to an improved device for holding and permitting the gradual escape or giving off of a disinfectant or like material, for instance, material for deodorizing, although it can be used for containing materials of different kinds and in different situations, as will be evident.

The invention is particularly designed for use in conjunction with garbage cans and the like, the device being constructed to eliminate the possibility of spilling which would be present if the container was one utilizing liquid disinfectant, the holder or container having a filling or a pad of absorbent material which holds the disinfectant or deodorizer and permits it to escape gradually by evaporation, the gases passing into the can, or other device in which the container is placed, by reason of openings provided for in the container.

The invention also consists in making a container which has spaced ribs at the top, or a similar structure which acts both to confine the absorbent in the container and to insure spaces between the element to which the container is fastened and the container itself for the escape of gas from the absorbent.

The invention is illustrated in the accompanying drawing, in which—

Figure 1 is a view of a can, the top part being shown in section with the container attached to the lid of a can. Fig. 2 is a top view of the container with the absorbent material removed, and Fig. 3 is a section through Fig. 2, but showing the absorbent material within the container.

It will be evident that the container can be used in a great many different situations, but in the drawing I show the container as applied to a can 10, such as is used for garbage and the like, the can having a lid 11 provided with a suitable handle 12. A container 13 is illustrated suspended beneath the lid on the inside, the container being of substantially flat form, this form being provided because it does not interfere

with the filling of the can. Garbage cans very often are emptied at intervals that are widely separated and are thus frequently filled to their capacity, and it is to permit this filling that the flat shape is devised, the container 13 shown in Fig. 1 having an open top which is spaced from the bottom of the lid by a washer 14, the washer being arranged around a screw 15 which passes through the container and through the washer and also through the top of the lid, being held in place by a nut 16. The washer insures the space 17 being left between the top of the container and the inside face of the top of the lid so that gases can escape from the container. To prevent spilling and to necessitate a slow evaporation of the disinfectant, I fill the container with absorbent material.

The container is shown in detail in Figs. 2 and 3 with a slight change. The container shown in Figs. 2 and 3 consists of a bottom 18 and sides 19, the general shape of the container being flat, and absorbent material 20 is placed in the holder, the absorbent material being felt, waste, fiber, or similar material, and being soaked or saturated with a suitable disinfectant which keeps the flies from a can and also acts to kill germs which may generate in the garbage or similar material contained in the can. Separated ribs 21 which are preferably arranged in the shape of a spider with turned-over ends 22 to embrace the flange 23 at the top edge of the side 19, act to confine the absorbent material in the container, the cut-away part between the ribs forming space to permit the thorough saturation of the material, the spaces insuring the escape of gases by evaporation from the absorbent, since the spaces between the ribs on the top edge, as at 24, formed by the ribs, the top edge of the sides of the container and the inner face of the lid, or other surface to which the device is secured, permit such escape.

One form of fastening means is shown in the drawing consisting of a screw 15 passing through the container and also into or through an element to which the container is affixed.

Having thus described my invention, what I claim is:—

The combination with the lid of a can, of a substantially flat container having imperforate bottom and side walls, a spider on

the top of the container, an absorbent material in said receptacle, and a screw passing through the center of the container and projecting above it for securing the container to the lid, the spider engaging the lid above the receptacle to act as a stop for the movement of the container toward the lid when it is fastened in place thus insuring spaces between the arms thereof and between the top edge of the side walls and the lid for

the escape of evaporated disinfectant from the container.

In testimony that I claim the foregoing, I have hereunto set my hand, this 9th day of July, 1913.

BARNIM L. BEHRENDT.
